UNITED STATES PATENT OFFICE

1,976,612

AUTOMATIC MUTUEL TICKET PROTECTOR

Fred Otto Guth, Chicago, Ill., assignor to Automatic Mutual Ticket Protector Corporation, Chicago, Ill., a corporation of Illinois

Application June 27, 1932, Serial No. 619,471

16 Claims. (Cl. 211—57)

This invention relates to an automatic mutual ticket protector, intended primarily for employment in connection with legal wagering in accordance with the pari-mutuel system.

5 While the device is intended for use in wagering, it is not intended to be limited thereto, since it possesses features of general application and is particularly applicable to any purpose in which the sale of tickets or tokens is to be terminated 10 at a precise moment determined by a person or instrument located at a point remote from the place or places where the sales of tickets occur.

One of the objects of the invention is to provide an improved mutual ticket protector.

15 A further object of the invention is to provide a machine of this class which is adapted to be operated from a distance to terminate the issue of further tickets.

20 A further object of the invention is to provide a machine of this type adapted to receive in convenient manner a complete supply of tickets.

25 A further object of the invention is to provide a machine of the class mentioned which readily can be united with a plurality of similar machines for operation in unison.

30 Other objects, advantages and capabilities of the invention will appear from the following description of a preferred embodiment thereof, taken in conjunction with the accompanying drawings, in which

Figure 1 is an elevation showing a plurality of machines located in ticket booths, the booths being shown in section from the ticket sellers' side;

35 Fig. 2 is an enlarged view of a machine shown partly in section;

Fig. 3 is a transverse sectional view of the machine;

40 Fig. 4 is an end elevation showing the manner in which the tickets are released after being locked;

Fig. 5 is a sectional detail view similar to Fig. 3, with the tickets locked;

45 Fig. 6 is a sectional detail showing the manner in which the ticket locking mechanism is secured in locking position until released by the releasing lever;

Fig. 7 is a perspective view, partly broken away, of a removable ticket box, whereby a supply of tickets may readily be installed within a machine;

50 Fig. 8 is a plan view of one of the tickets which may be employed;

Fig. 9 is a similar view of a modified form of ticket;

Fig. 10 is a diagrammatic view showing the 55 manner in which the machines may be controlled

from a distance to lock the tickets in place; and Fig. 11 is a similar view of a modified form of wiring.

In one of the principal uses to which the machine of the present invention may be placed, 60 that is, in the system of legalized wagering known as the pari-mutuel system, ticket sellers sell to the public tickets, each of which represents a wager on a certain eventuality in a coming race. The probable odds are determined on the basis 65 of the tickets sold, which odds are announced at regular intervals. At or slightly before the starting of the race, usually on the ringing of the post bell, the sale of tickets ceases, and the odds payable on the winning tickets are readily calculated on the basis of income and the number of tickets which are to be paid.

It frequently happens that the duration of a race, for example, a furlong race, is very short, 75 so that before the auditors can check up on the condition of ticket sales, the eventuality may be largely decided. That is, in a short race, the winner may be apparent in a matter of seconds.

One of the abuses to which the pari-mutuel system has been subjected is that in some cases a 80 dishonest ticket seller is able to abstract winning tickets which pay a substantial profit at the expense of the other persons who have legitimately paid for their tickets on the basis of a fair chance. It will readily appear from the following description of a preferred embodiment of my machine, 85 that its use effectively prevents this abuse, since any number of machines can be locked from a remote point at the moment of starting the race or any predetermined time before such starting. 90

In the drawings, particularly Fig. 1, I show a plurality of machines 12, each located in a booth 13 in which the ticket seller is accommodated. Each booth is provided with a grilled window 14 through which the tickets may be sold and paid for. Each machine 12 comprises a casing 15, the upper flat top plate of which may suitably be located at the bottom edge of the window. On the inner side of the machine I may provide a counter 16.

The machine is secured to the walls of the booth in any suitable manner, for example, by means of brackets 17. In a position preferably in alignment with the counter 16, the casing 15 comprises a horizontal plate 18 forming part of the outer wall of said casing. A sloping wall 19, 105 also forming part of the outer wall of the casing, extends upwardly and rearwardly slightly from the wall 18 and terminates at the flat top plate referred to above.

The sloping wall 19 is provided with an elongated opening 20 which occupies most of the surface of the plate 19, this opening being relatively long in the horizontal direction and being 5 relatively low in the vertical direction. This opening is adapted to receive the ticket box 21 which is shown in perspective view in Fig. 7.

A housing 22 is provided within the casing 15 adjacent the opening 20, which snugly receives 10 the box 21 in the manner shown in Fig. 3. Suitable means are provided for holding the box 21 in desired position within the housing 22. Such means are shown, by way of example, as spring clips 23, the outer ends of which project outwardly adjacent the lower edge of the housing 22, these clips being adapted to spring upwardly after the box is inserted and hold same until it is desired to remove the box for examination by auditors and/or for replacement.

20 The box 21 comprises a base 24, a rear wall 26, and end walls 27. It is preferably open at both top and front. The box 21 comprises a plurality of partitions 28 which may be located parallel to the end walls 27 to which they are equal in 25 dimensions. The partitions 28 divide the box into any desired number of cells 29, each cell being adapted to receive a stack of tickets, each stack corresponding to a different wager. For example, the tickets in the first cell may represent 30 a wager on a certain horse "to win". In the next cell the wager may be upon another horse "to win". Other machines may be used for different priced tickets, and for different eventualities in the same event. The nature of the wager 35 which each stack of tickets represents has no relation to the invention since they may be varied in any way desired by the public.

In the base 24 of the box 21, in each cell thereof, is provided an opening 30 through which pass 40 the means adapted to lock unsold tickets in place at a predetermined moment. The housing 22 is provided at the top and bottom with openings 31 which are in alignment with the openings 30 when the box 21 is installed in the machine. 45 The housing 22 is reinforced at the top and bottom by means of longitudinal bars 32 and 33 which are also provided with openings 34 and 35 in alignment with the openings 30 and 31.

50 The bar 33 is rigidly connected to the base of the casing 15 by means of bars 36 suitably secured at either end of the casing 15, these bars being in the same longitudinal plane as the axes of the openings 30, 31, 34 and 35, so that they may serve as guides for the locking frame in addition to supporting the housing 22.

55 The locking frame consists essentially of a bar 37 carrying at each end sleeves 38 which ride upon the bars 36. The bar 37 carries a series of rods 39, one for each cell, said rods 39 extending upwardly and being aligned with the aligned openings 35, 31, 30 and 34. The upper ends of the rods 39 are sharply pointed, and these pointed ends are located within the openings 35 in the bar 33 when the locking frame is in its unlocked 60 position as shown in full lines in Fig. 3.

65 When the frame is in locking position, as shown in dot and dash lines in Fig. 3, the upper ends of the rods 39 are projected through the openings 34 in the bar 32 and, extending through openings in the tickets as will hereinafter be described, the tickets are thus locked into the machine.

70 At each end the bar 37 is connected to a flexible support 40 which extends upwardly and rearwardly slightly at the same inclination as the

bars 36. The wires 40 pass over pulleys 41 and 80 42 which may suitably be mounted on rods 43 and 44 which extend through the casing 15 adjacent its upper edge. The wires 40 are connected to each end of a heavy bar 45 which is adapted for vertical movement near the rear wall of the machine, a suitable guide 46 being provided on each end wall of the casing 15 in order to limit the movement of the bar 45.

81 It will be readily understood that the weight of the bar 45 tends to raise the locking frame into the locking position. The bar 37 carries, adjacent its center, brackets 47 upon which is pivotally mounted a dog 48. The dog 48, as shown more clearly in Fig. 6, carries a forwardly projecting portion 49 which normally projects forwardly under the influence of gravity. The dog 48 also comprises an abutment leg 50 which prevents excessive forward movement of the forwardly projecting portion 49.

90 The dog 48 is adapted to cooperate with a latch element 51 which is pivotally mounted in a housing 52 located within the casing. The latch 51 comprises an elongated end 53 and is normally held in latching position by means of a spring 54. In order to enable the latch 51 to resist the load applied to it by the dog 48, an abutment member 55 is provided which is pivotally mounted on a substantially vertical axis and is adapted to be attracted by an electromagnet 56 so 100 as to release the latch 51. A spring 57 tends to move the abutment 55 into the position shown in Fig. 3, the action of the springs 54 and 57 being to lock the latch 51 automatically when the electromagnet 56 is deenergized.

105 It will readily be understood that when the magnet 56 is energized, the locking frame is released and the weight 45 causes it to move upwardly so as to lock the tickets in their cells. When the magnet 56 is deenergized, the latch 110 51 returns to its normal position, and when the locking frame is moved downwardly, in the manner hereinafter described, the dog 48 moves on its pivot past the latch 51 and thereafter moves forwardly to engage said latch and hold the 115 locking frame in unlocked position.

120 On the rear side of the bar 37 I mount brackets 58 upon which is pivotally mounted a gravity dog 59. This dog comprises a latch portion 60 and a weight 61. The latch portion 60 is adapted to engage a latch element 62 provided on the rear side of the housing 22. The latch portion 60 and the latch element 62 are provided with sloping surfaces adapted to coact to permit the latch portion 60 of the dog 59 to pass the latch 125 element 62. After this passing, the weight 61 moves the dog 59 into the locking position shown in dash and dot lines in Fig. 3. The dog 59 carries a rearwardly extending crank 63 which is operated to unlock the engagement between 130 the latch elements 60 and 62 which will hereinafter be described.

135 Adjacent each end of the bar 37 I mount rearwardly extending plates 64 by means of which the locking frame is returned to unlocked position. Through each machine extends a shaft 65 which rigidly carries arms 66 which are adapted to engage the plates 64. On the shaft 65 is also mounted a rod 67 which is adapted to engage the crank 63. In order to effect this return, the shaft 65 is rotated in the clockwise direction, as viewed in Fig. 3. The initial effect of this movement is to bring the rod 67 into engagement with the crank 63 and release the lock- 140 145 150

ing engagement between the latch elements 60 and 62.

As the movement continues the arms 66 engage the plates 64 and force the frame downwardly until locking engagement is established between the dog 48 and latch element 51. The shaft 65 should now be returned to its initial position so that the weight of the arm 66 should not be added to the movement of the locking frame 10 which must be overcome by the weight 45. This may suitably be effected by means of a spring 68 which may act upon the actuating handle 69 which is rigidly mounted on the shaft 65.

As shown in Fig. 1, any number of machines 15 may be located in a row and their shafts 65 may be secured together in any suitable manner so as to enable them to act as a unit.

The actuating handle 69 is located at one end of the row of machines and may be located in a 20 separate booth as shown in Fig. 1, so as to prevent actuation by any ticket seller. It is preferred to provide a suitable lock so that the handle 69 can be actuated only by an authorized auditor after the tickets are checked. A suitable lock is 25 shown in Fig. 2. This lock may comprise an abutment member 70 in which is slidably mounted a bolt 71 adapted to enter an opening in the handle 69. The bolt 71 may be actuated by a key-operated lock barrel 72 of known type.

30 An electric conduit 73 extends through the casings 15 of the series of machines and within each machine is provided a T 74. This conduit system provides for the admission of conductors for supplying energy to the electromagnets 56 when desired.

Along the plate 18 I provide a plurality of 35 spring clips 75, one in front of each cell 29 of the ticket box 21. The purpose of these clips is to hold tickets returned after issue of succeeding tickets. Above the position of each cell of the ticket box 21 I provide means, such as hooks 75' for supporting cards 76, which may provide information, such as the names of horses or the like, which indicate to the ticket seller in a convenient manner, the nature of the wager or transaction which tickets therebelow represent.

40 As shown in Figs. 8 and 9, each ticket comprises indicia, such as numbers and words identifying the wager which it represents. Other indicia which identify the location and the date, 45 may be applied if desired. In addition, the tickets of each stack are numbered serially. In Figs. 8 and 9, the serial number shown is "34". The serial number is preferably applied at the lower edge of the ticket so that it may readily be seen by auditors and checkers.

45 As shown in Fig. 8, each ticket 76 is provided with a round opening 77 adapted to come into alignment with the rod 39 of the cell in which the tickets are located. This opening is preferably placed in the rearward part of the ticket so as to minimize the danger of engagement of the ticket seller's finger by the sharply pointed rods 39 when the locking frames are released. It has been 50 found, in practice, that an upwardly moving pin offers little danger to the ticket seller since the ticket seller's fingers are normally at the surface of the stack and remote from the upper end of the ticket spaces so that they slip off before they 55 are impaled against the housing 22. It is also found that misplaced tickets at the top of the stacks are carried up and impaled.

50 As shown in Fig. 9, the opening 78 of the ticket may be elongated so that if a few tickets at the 75 top of the stack are moved outwardly by accident,

the rod 39 will pass through the elongated opening. In this case the rods 39 and associated parts are moved forwardly from the position shown in the drawings, so that they align with the forward portion of the opening 78, as shown in Fig. 9.

Means are provided whereby the machines are locked simultaneously from a remote point. This may suitably be done by an electric circuit which energizes all of the magnets 56 simultaneously. These magnets 56 may be connected in parallel circuit with the post-bell 79 so that the machines may be locked by the same switch 80 which is actuated to ring the post-bell. A simple circuit for this purpose is shown in Fig. 10, which is adapted to be operated by a battery 81.

In Fig. 11 is shown a circuit whereby the usual alternating current from the mains may be employed. This circuit comprises a transformer 82, the secondary of which is connected to the bell 79 and magnets 56. This secondary circuit includes the switch 80 and also a switch 83 which is held in closed position by means of an electromagnet 84 which is connected across the secondary of the transformer 82. A battery 85 is provided which comes into operation automatically in the event that the power line supply fails. When the magnet 84 is deenergized, a spring 86 pulls the armature 83 toward the contact 87 so as to break the secondary circuit and change over to the battery circuit.

The operation is as follows:

A race having been run, the ticket boxes are locked by means of the rods 39. The exposed serial numbers or stop numbers of the tickets have been noted by auditors so that the numbers of the tickets to be paid are definitely recorded. This information having been received, an auditor or other official unlocks the handle 69 and actuates same to move the locking frames into unlocked position in which they are held in the manner described above. The handle 69 is then returned and locked in position. The ticket boxes are then removed and checked and the odds are determined in due course.

The cards 76' are changed to correspond to the 60 coming event and each machine is supplied with a box of tickets, the serial numbers of the top tickets preferably being "1". The ticket seller may now proceed to sell tickets and the exposed serial numbers at the lower edges of the tickets will enable the odds to be rapidly calculated at any time, this operation being done at periodic intervals so as to inform the public of the probable odds. In the event that any ticket is returned after later tickets are issued, the same may be held by the appropriate clip 75 so that the auditor or other checker may immediately see the correction which has to be made in the normal reading, as indicated by the serial number of the topmost ticket.

65 As the start of the race approaches, the post bell 79 is sounded, this serving as a signal that betting is terminated. When the switch 80 is closed to ring the bell 79, the magnets 56 are energized and the locking frames are released so that the rods 39 project upwardly through the openings in the tickets and into the bar 32. After this moment no ticket can be removed from the ticket box without the same being mutilated. The elongated opening 78 in the ticket 76, as shown in Fig. 9, has a tendency to mutilate the ticket if removal is attempted by tearing the ticket in half so that the difficulty of fraud on the part of the ticket seller is enhanced.

70 After the race is run, as described above, the

serial numbers of the tickets may be rapidly taken, the odds determined, and thereafter the tickets are removed and checked.

Although the invention has been described in connection with the specific details of a preferred embodiment thereof, it must be understood that such details are not intended to be limitative of the invention except in so far as set forth in the accompanying claims.

Having thus described my invention, what I claim as new and desire to secure by Letters Patent of the United States is:

1. In a device of the type described, in combination, a ticket box provided with a plurality of ticket cells, said box being provided with openings extending into each cell, means adapted to be projected through said openings to lock the tickets in said cells, and means adapted to be operated from a distance to release said locking means.
2. In a device of the type described, in combination, a housing, a ticket box removably received by said housing, locking means adapted to project through the ticket box and housing to prevent removal of said box and said tickets, a latch adapted to hold said locking means in unlocking position, and electrical means for releasing said locking means.
3. In a device of the type described, in combination, a cabinet, means for supporting a ticket box thereon, said box being adapted to receive a series of stacks of tickets, locking means adapted to lock said box and contents to the cabinet, means in said cabinet tending to move said locking means to locking position, a latch adapted to prevent said movement, means without the cabinet for resetting the locking means, and means without the cabinet for releasing said latch.
4. In a device of the type described, in combination, a cabinet, means for supporting a ticket box thereon, said box being adapted to receive a series of stacks of tickets, locking means adapted to lock said box and contents to the cabinet, means in said cabinet tending to move said locking means to locking position, a latch adapted to prevent said movement, a lever without the cabinet for resetting the locking means, a lock for holding said lever against unauthorized actuation, and means without the cabinet for releasing said latch.
5. In a device of the type described, in combination, a cabinet, means for supporting a plurality of stacks of tickets thereon, locking means adapted to lock said tickets to the cabinet, means in said cabinet tending to move said locking means to locking position, a latch adapted to prevent said movement, means without the cabinet for resetting the locking means, and means without the cabinet for releasing said latch.
6. In a device of the type described, in combination, a cabinet, means for supporting a plurality of stacks of tickets thereon, locking means adapted to lock said tickets to the cabinet, means in said cabinet tending to move said locking means to locking position, a latch adapted to prevent said movement, a lever without the cabinet for resetting the locking means, a lock for holding said lever against unauthorized actuation, and means without the cabinet for releasing said latch.
7. In a device of the type described, in combination, a ticket box provided with a plurality of ticket cells, each cell being adapted to receive stacks of tickets provided with aligned openings,

said box being provided with openings extending into each cell in alignment with said openings, rods adapted to be projected through said openings to lock the tickets in said cells, a support carrying said rods for movement in unison, and means adapted to be operated from a distance to release said support and rods.

8. In a device of the type described, in combination, a housing, a ticket box removably received by said housing, locking means comprising a series of rods adapted to project through the ticket box and the housing to prevent removal of said box and said tickets, a latch adapted to hold said locking means in unlocking position, and electrical means for releasing said locking means.

9. In a device of the type described, in combination, a cabinet, means for supporting a ticket box thereon, said box being adapted to receive a series of stacks of tickets, locking means comprising a plurality of rods adapted to lock said box and contents to the cabinet, each of said rods adapted to be projected through a stack of tickets, means in said cabinet tending to move said locking means to locking position, a latch adapted to prevent said movement, means without the cabinet for resetting the locking means, and means without the cabinet for releasing said latch.

10. In a device of the type described, in combination, a cabinet, means for supporting a ticket box thereon, said box being adapted to receive a series of stacks of tickets, locking means comprising a plurality of rods adapted to lock said box and contents to the cabinet, each of said rods adapted to be projected through a stack of tickets, a weight in said cabinet tending to move said locking means to locking position, a latch adapted to prevent said movement, means without the cabinet for resetting the locking means, and means without the cabinet for releasing said latch.

11. In a device of the type described, in combination, a cabinet, means for supporting a ticket box thereon, said box being adapted to receive a series of stacks of tickets, locking means adapted to lock said box and contents to the cabinet, said locking means including a series of rods each adapted to extend through said ticket box and through one of said stacks, a weight in said cabinet tending to move said locking means to locking position, a latch adapted to prevent said movement, a lever without the cabinet for resetting the locking means, a lock for holding said lever against unauthorized actuation, and means without the cabinet for releasing the said latch.

12. In a device of the type described, in combination, a cabinet, means for supporting a plurality of stacks of tickets thereon, locking means adapted to lock said tickets to the cabinet, said locking means comprising a plurality of rods, each rod being adapted to project through one of said stacks, means in said cabinet tending to move said locking means to locking position, a latch adapted to prevent said movement, means without the cabinet for resetting the locking means, and means without the cabinet for releasing said latch.

13. In a device of the type described, in combination, a cabinet, means for supporting a plurality of stacks of tickets thereon, locking means adapted to lock said tickets to the cabinet, said locking means comprising a plurality of rods, each rod being adapted to project through one

of said stacks, means in said cabinet tending to move said locking means to locking position, a latch adapted to prevent said movement, a lever without the cabinet for resetting the locking means, a lock for holding said lever against unauthorized actuation, and means without the cabinet for releasing said latch.

14. In a device of the class described, a receptacle adapted to receive a plurality of stacks of apertured tickets, a plurality of ticket locking rods, means for simultaneously projecting said rods through the apertures of the tickets of the several stacks to lock said tickets against removal from the receptacle, and means for controlling the projecting means from a remote point.

15. In a device of the class described, a receptacle adapted to receive a plurality of stacks of apertured tickets, apertures in the receptacle with which may be aligned the apertures of the tickets of the several stacks, a plurality of ticket locking rods normally lying outside of that part

of the receptacle occupied by the tickets, and means adapted when operated simultaneously to project said rods through the receptacle apertures and the ticket apertures with which the receptacle apertures are aligned to lock said tickets against removal from the receptacle.

16. In a device of the class described, a receptacle adapted to receive a plurality of stacks of apertured tickets, apertures in the receptacle with which may be aligned the apertures of the tickets of the several stacks, a plurality of ticket locking rods normally lying outside of the part of the receptacle occupied by the tickets, means adapted when operated simultaneously to project said rods through the receptacle apertures and the ticket apertures with which the receptacle apertures are aligned to lock said ticket against removal from the receptacle, and means for controlling the operation of the projecting means from a remote point.
